Frederick L. Boehlert, Buffalo, N. Y.

Application March 7, 1947, Serial No. 137,421

Term of patent 3½ years

(Cl. D17—8)

To all whom it may concern:

Be it known that I, Frederick L. Boehlert, a citizen of the United States, residing at Buffalo, in the county of Erie and State of New York, have invented a new, original, and ornamental Design for a Combined Collar and Tie Holder, of which the following is a specification, reference being had to the accompanying drawings forming part thereof.

In these drawings:

Fig. 1 is a front elevation of the combined collar and tie holder embodying my invention.

Fig. 2 is a top plan view thereof.

Fig. 3 is a rear elevation thereof.

Fig. 4 is an end elevation thereof, viewed from the left of Fig. 3.

I claim:

The ornamental design for a combined collar and tie holder, substantially as shown.

FREDERICK L. BOEHLERT.
